(57) **CLAIM**

The ornamental design for a storage bag, as shown and described.

DESCRIPTION

FIG. 1 is a front elevation view of a storage bag showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a prospective view thereof; and,

FIG. 8 is another prospective view thereof, showing an alternative, open configuration of the storage bag.

1 Claim, 8 Drawing Sheets
